BOMBING GAME APPARATUS

Fred M. New, New York, N. Y.

Application March 23, 1940, Serial No. 325,627

5 Claims. (Cl. 273—101.1)

This invention relates to game apparatus and more particularly to apparatus in which airplanes or similar devices are used for "bombing" or like purposes to hit a target or targets.

5 It is a feature of this invention to provide means for directing from an airplane or similar movable apparatus a light beam simulating the trajectory of a "bomb" to "hit" said target.

10 It is another feature of this invention to provide means for indicating at the location of said target if the latter is properly "hit" or not.

15 It is still another feature of this invention to relatively move said airplane or similar device at varying speeds in a predetermined path and above said target to be "hit."

20 It is a further feature of this invention to direct a light beam for aiming purposes from said movable device at said target.

25 Still another feature of this invention is to provide remote indicating means with respect to said "hit" target for signaling that said latter is properly aimed at.

30 Yet, another feature of this invention resides in the provision of light means adapted to illuminate the said target whereby when said light beam from said airplane is substantially in alignment with one of said light means and upon releasing of a control device another of said light means is switched over to signalize that a proper "hit" has been effected or established.

35 It is still a further object of the present invention to provide an educational amusement device in which the releasing of a "bomb" and establishment of an actual "hit" of a target or targets by said "bomb" is simulated by flashing on of direct or indirect illuminating means.

40 Still a further object of the present invention is to provide a coin operated apparatus having a plurality of targets forming a target course and arranged on a platform (the targets being normally in a dimly lighted atmosphere) and an airplane thereabove, preferably the airplane being relatively movable to the said platform and projecting through an aperture facing said target 45 course, a beam of light on the platform, the beam of light selecting or spotting out successively the targets during movement of said airplane forming a light projector means, remote means being further provided operable for establishing an electrical contact at a moment when the light beam strikes a target to bring into effect illuminating means indicating that a "hit" of said target has been made.

50 It is still another object of the invention to provide indicating means in the movable airplane,

at the target, as well as on a score board to simultaneously signalize the establishment of a "bomb hit."

5 It is a still further object of the present invention to provide releasing means remote from the said airplane and said targets on the platform adapted to be manipulated by the operator, who views said light beam laterally thereof to spot out the target to be "hit" by said light beam. This feature particularly differentiates game apparatus made in accordance with this invention from those known and in use as "shooting" game apparatus wherein an aiming device including a gun-like implement with sight means is employed for bringing into alignment the eye of the operator 10 with said sight means and target or targets, movable or otherwise. In such devices electrical contact with the "shooting" or aiming device is established when such alignment condition is brought about.

20 In further contradistinction to said known "shooting" or aiming devices the device at present contemplated brings into play the senses of judging, estimating and approximating the timely relationship between and coincidental positioning 25 of two or more relatively movable objects, for example, of a movable beam of light and a fixed target, whereby the ability and skill of a person or operator is developed. The device lends itself as an amusement instrumentality in which the 30 operator is also an eye witness or observer of the "bombing" scene-in-action.

35 The foregoing and other objects and features of the invention will become more clearly apparent from the following description, which is descriptive of a preferred embodiment of the invention illustrated in the accompanying drawings. However, the embodiment herein shown and described being for purposes of illustration only, it is to be understood that such modifications may 40 be made, when desired, within the scope and spirit of the invention as claimed.

45 In the drawings:

Fig. 1 is a circuit diagram of the electrical connections employed for carrying out the invention.

Fig. 2 is a perspective fragmentary view of an apparatus made in accordance with the invention.

Fig. 3 is a top view of the driving mechanism employable in the invention.

Fig. 4 is a fragmentary elevational view shown 50 in section on an enlarged scale of the apparatus shown in Fig. 1.

Figs. 5, 6 and 7 are top views of parts of the apparatus, shown in Fig. 4, taken along lines 5, 6, 7, respectively.

Referring now to the drawings, and more particularly to Figs. 2 and 4, there is provided a housing 10 having a front window 11 whereby the inside of the housing 10 may be viewed by the operator and observer (not shown). Within housing 10, there is arranged a substantially horizontal platform 12 upon which there are disposed a plurality of targets 1a', 2a' . . . 6a' . . . 10a', said targets being successively arranged with respect to each other and spaced from one another. The targets may be of any desirable form and may represent any desired target object or objects providing a target course. The platform may be representative of any desired landscape which includes roads with armored cars, tractors, battle ships, airplane hangars, etc., which may be dimly illuminated by indicating means or lamps, as, for example, 14, 14a (Fig. 4). Light projector means 15 simulating a bomber or like aircraft device is suspended on a bracket 16 which is rotatably mounted in a partition 17 of housing 10. Bracket 16 has a vertical extension 18 which projects within a box 19 within which is disposed the driving mechanism for bracket 16 and certain electrical connections later described.

Light projector means 15 is provided with a tubular extension 20 having an aperture positioned above and facing said target course and said indicating means. Light projector means 20 is adapted to emit through said aperture light rays successively and continuously upon the said target objects of said target course on the platform 12. The beam of light 21 assumedly simulates the trajectory of a "bomb" when released or dropped from a bomber.

When the bomber 15 (upon insertion of a coin (not shown) into coin slot slide 28) is made to follow a predetermined path, as will be described further below, and at the moment the light beam 21 traverses and thus spots out a selected target, say, for example 6a' (Fig. 4) and the bomb release 22 (Fig. 2) is operated, thereby actuating rod 23, then at this instant red light lamp L₆ will be brought into operation (through the circuit hereinafter described) thereby simulating an explosion and a proper "hit" will simultaneously be indicated on the board 25 arranged at the top of housing 10. In order to provide passages for the light rays from lamps 14 and L₆, respectively, and other corresponding lamps to the said targets, openings 26, 27 are provided in platform 12. Every time the bomb release lever or button 22 is operated the "dropping of a bomb" will be indicated on board 25, whether a "hit" is made or not. After, for example, ten "bombs" are released, which will be successively indicated on board 25, the game automatically stops functioning, and it will require the insertion of another coin in coin slot 28 of the apparatus to put the game again in operation.

Within casing 19, there is mounted an electric motor 30 provided with a rotatable shaft 31 upon which is fixed a pulley 32 over which is trained a belt 33, the latter also being trained over a preferably larger pulley 34 fixed to shaft 18 and bearing against a bushing 35. Provision may be made for varying the driving speed of pulley 34. To this end, there may be provided a cam 36 fixed to rotate with shaft 31, said cam 36 being engaged with a cam follower 37 rotatably mounted on bracket 38. Bracket 38 is pivoted at 39 to a bearing 40 which may be secured on partition 17, and has rotatably mounted at its end 41 a grooved pulley 42 constantly urged against belt 33 by a

spring 43, one end of which is attached to bracket 38, and the other end of which may be secured to a stud 44 on partition 17. It is well understood that as shaft 31 rotates the follower 37 will be caused by engagement with cam 36 to vary the pressure of pulley 42 on belt 33, thereby varying the speed of pulley 34 and shaft 18 connected thereto. Therefore airplane 15 may follow a circular path at non-uniform or varying speed, thereby making the apparatus more interesting and more difficult to manipulate.

Shaft 18 is supported in a bracket 45 mounted on partition 17. Fixed to bracket 45 is a disc 46 having three brush arms 47, the latter contacting respectively the contact rings 48, 49, 50 mounted on disc 51 rotatable with shaft 18, said contact rings being the electrical connections to white and red light lamps WL and RL housed in the airplane 15 (Figs. 1 and 5). The underside 52 of disc 51 has a pusher or switch member 59 which, during rotation of disc 51, will respectively and successively actuate switch contacts 1a, 2a, 3a etc., circumferentially arranged on partition 17. It is evident that the pusher or switch member 59 may be of any predetermined length and width or may be made telescopically adjustable in length to maintain electrical contact as long as desirable between, for example, the leaves 53, 53a of contact 6a or 54, 54a of contact 7a, etc.

The operation of the game apparatus together with the electrical connections shown in Fig. 1 will now be described.

Upon insertion of a coin (not shown) in coin slot 50 of slide 28, the latter being retracted, the following circuit will be established:

Contact will be closed between A and B (Fig. 1) and timer W will also be closed (in a manner well known in the art) and thus put primary P₁ of transformer T₁ across power source S.

Closing of A and B which occurs momentarily, energizes reset coil RC of bomb counter sections C₁—C₂ allowing the same to be reset to zero through the following circuit:

Contact point B, leads 100, 101, 102, RC, leads 103, 104, 105, 106, terminals E—F of secondary P₂ of transformer T₁ to ground G₂ back to contact A through ground G₁ and lead 100a. Reset coil RC has an armature which is engageable with a dog of the bomb counter ratchet wheel. Every time the bomb release 22 is operated pointer 55 of bomb counter C₁—C₂ moves forwardly one digit, that is from zero (0) to one (1), from one (1) to two (2), etc., which progressive movement of pointer 55 is brought about by an electrical system described herein below. When the said coin is inserted to start operation of the machine the reset coil RC will attract its armature disengaging said dog from said ratchet wheel and causes the latter while being under spring tension to return to its initial position in which pointer 55 will be set at zero (0). This dog and ratchet arrangement under control of a relay is well known in the art and is therefore not deemed necessary to be set forth in more detail. Counter section C₁ functions as an end switch which is mechanically connected to counter section C₂. Pointer or switch arm 55 and arm 56 of C₂ are both fixed to a common shaft 57 and therefore will rotate simultaneously in successive stages, 70 arm 56 passing from zero (0) over terminals 135, 136, etc., to switch on bomb lamps B₁, B₂, B₃, etc., arm 56 being connected by means of leads 145, 125, 105 to secondary P₂ of transformer T₁. One leg of each bomb lamp is arranged to contact the 75

rotatable switch arm 56, the other leg of each bomb lamp being grounded at G₅, making the return through G₂ to the secondary P₂ of transformer T₁.

5 When A and B will be closed, then contacts A and C (normally closed) will open, thereby breaking electrical lock of all hit relays R₁, R₂, R₃, etc., R₁₀. Relays R₁ to R₁₀ are normally open and some or all will be closed during the operation of 10 the apparatus. In resetting C₁—C₂ as aforesaid, switch relay SR will be deenergized as its circuit is open because switch arms 55, 56 are returned to zero and no further electrical connection is established with the secondary P₂ of transformer 15 T₁. Upon deenergization of said relay SR contact blades at switch S₁ and switch S₂ will be closed (normally open under spring tension); switch S₂ thus energizes motor M through the following circuit: Switch S₂, lead 107, motor M, 20 lead 108, primary P₁ of transformer T₁, lead 109, back to switch S₂. Mechanically connected to motor M as by means of a shaft 58 is a switch arm 59 of the contactor unit of target TC. When 25 motor M is energized switch arm 59 will rotate over contact points 1a, 2a, 3a, etc., to 10a successively and continuously in the direction of the motor drive.

As above mentioned deenergization of switch relay SR also causes closing of switch S₁, which 30 thus completes the circuit for bomb counter relay BC and white light lamp WL of the airplane or bomber 15 in the following manner:

For white lamp WL: S₁, lead 110, ground G₃, ground G₂, terminals E—F of secondary P₂ of 35 transformer T₁, leads 106, 111, 112, WL, leads 113, 114, 115 back to S₁;

For bomb counter BC: lead 110, ground G₃, ground G₂, terminals E—F of secondary P₂ of transformer T₁, leads 106, 111, 118, 116, bomb release 40 momentary contact BMC₁, lead 117, coil BC, lead 115, back to S₁. BMC₁ is caused to close by momentary contact relay MCR, the latter being energized through the following circuit, when bomb release BR is closed: S₁, lead 110, ground G₃, ground G₂, terminals F—E of secondary P₂, 45 leads 106, 111, 118, 119, BR, lead 120, MCR, leads 121, 114, 115 back to S₁.

When bomb release 22 having the contacts BR is closed the circuit for MCR (momentary contact 50 relay) is completed and momentary contacts BMC₁ and BMC₂ are momentarily closed by action of energized MCR.

Closing of BMC₁ by MCR operates red light RL of airplane and further bomb counter relay 55 BC through the following circuit: BMC₁, leads 116, 118, 111, 106, terminal E—F of secondary P₂ of transformer T₁, ground G₂, ground G₃, lead 110, switch S₁, leads 115, 114, 113, red light RL back to BMC₁ and also from BMC₁ to BC through lead 60 117 placed in parallel with the former circuit.

Energization of bomb counter relay BC causes stepwise advancement of counter sections C₁ and C₂ through conventional ratchet and wheel mechanism hereinabove mentioned.

65 As set forth above with respect to bomb release 22 each operation thereof will result in the pointers or contact arms 55, 56 of counter sections C₁—C₂ being forwardly moved in one-digit stages and corresponding bomb lamps B₁ to B₁₀ are thus switched on. Now, after, say, ten bombs have been thus released switch or contact arm 55 will have reached the dotted line position at point ten of the dial, whereby the following circuit will be closed: Point 10, lead 125, switch relay SR, ground G₄, ground G₂, terminal F—E of sec-

ondary P₂ of transformer T₁, leads 106, 105, 125, 126 to pointer 55 back to point 10.

By this circuit switch relay SR will be energized, and made operable to open switches S₁ and S₂, thereby deenergizing again the hereinabove mentioned circuits for motor M, relay BC, plane lights WL and RL and relay MCR. 5

Simultaneously with the closing of BMC₁ by momentary contact relay MCR, bomb release momentary contact BMC₂ will also be closed. 10 Thus the following circuit for hit relays R₁ to R₁₀ may be established; all hit relays are connected on the one hand to leg 127—131 (which is joined to leads 128, 129, contacts A—C, lead 100a and ground G₁) and on the other hand through relay 15 contacts R_{1a} to R_{10a}, leads 130, relay coils to the other leg 118' (which is joined to leads 118, 111, 106, terminal E—F, secondary P₂ of transformer T₁, and ground G₂). Leads 130 further connects with target contactor TC and its terminals 1a to 20 10a over which switch arm 59 slides, which in turn is connected through lead 112' to momentary contact BMC₂.

Now, referring to Figs. 2 and 4, airplane 15 is revolving and the light beam 21 is approaching 25 target 6a'. If, at the moment said beam 21 is thrown on target 6a' bomb release lever 22 is operated bomb release contacts BR (Fig. 1) will close and the circuit containing the latter will be established, as above described. 30

In Fig. 1, for example numeral 6a on target contactor TC represents the relative position of said light beam 21 on target 6a' (Fig. 4), switch arm 59 being mechanically connected to motor M through shaft 58 will thereby establish a circuit causing hit light H₆ on board 25 (Figs. 1 and 2) and target red light L₆ (Figs. 1 and 4) to be illuminated. This circuit is as follows: Momentary contact BMC₂, lead 127—131, relay contact R_{6a} (closed by energization of coil R₆), lead 130, 35 coil of relay R₆ and leads 128, 129, contacts A—C, ground connections G₁—G₂, terminals F—E, secondary P₂ of transformer T₁, leads 106, 111, 118, 118', coil of relay R₆, lead 130, relay contact R_{6a}, lead 131—127 back to BMC₂. Hit light H₆ 40 and target red light L₆ are connected in parallel and across leads 127a and 132; the lead 132 connecting with contact 6a of target 6a' through lead 130 and said contact 6a of target 6a' connecting with lead 112' back to BMC₂. Lamps 45 H₆ and L₆ are illuminated during closing of relay R_{6a} and will remain so until the end of the game because, although switch arm 59 (operated by motor M) will immediately pass over contact of target 6a' and thereby open the respective circuit at said contact, the current will be shunted through the now engaged contact at R_{6a}, thereby maintaining the circuit formed by leads 131, 128, 129, contacts A—C, ground connections G₁—G₂, secondary P₂ of transformer T₁, leads 50 106, 111, 118, 118', lead 127, coil of relay R₆. It is to be understood that bomb release switch BR is of the momentary type and after being operated for closing its circuit will automatically and instantly open again said circuit (before pusher 65 arm 59 will move from contact 6a of target 6a' to that of target 6a' etc.).

Only when bomb release lever 22 (BR) is operated at the exact moment that pusher or switch member 59 causes connection between the 70 leaves of any of the contacts 1a to 10a will a "hit" of the "bomb" be established and indicated at the board by a corresponding lit "hit" lamp and by a lit "bomb" lamp signalizing the number of "bombs" already used up for establishing said hit. 75

Selection by the operator of the target to be "hit" is made through light beam 21, which coordinates the position of a target on platform 12 with the position of the corresponding contact on partition 17, for example, with respect to target 6a', switch leaves 53, 53a (of target contact 6a) and pusher member 59. After a "hit" has been made or missed another target may be selected in a similar manner until ten (10) "bombs" 10 are released by manipulating bomb release 22 (BR) ten times. Upon insertion of a further coin the game may then be repeated for a further operation.

It is apparent that the plane 15 may be made to 15 revolve and the platform and targets thereon may remain stationary or any two or more of said airplanes, platform and targets may be made to relatively move and preferably at different speeds. It is further evident that any conventional switching arrangement (not shown) may be provided to cause instant illumination of lamp 14 (Fig. 4) only, when light beam 21 of airplane 15 is approaching target, say, 6a', in order to make the game more attractive and to direct the 20 eye of the observer and operator to said target proper. From the above it will be seen that there has been provided according to this invention a game apparatus comprising a substantially horizontal platform, at least one target disposed at said platform, electrically operable indicating means positioned below said target for illuminating the same, light projector means simulating an aircraft for aiming at said target and having an aperture, means to continuously 25 move said projector means in a predetermined path above and relatively to said target, said projector means being arranged in superposed relation to said target and said indicating means and being adapted to emit through said aperture a beam of light simulating bomb dropping, said light beam being directed toward said platform and traversing said target when said projector means is moved along said path, hand-operated switch means simulating bomb releasing mechanism and including an electric circuit, and electric means coordinated to said target and includable in said circuit, said switch means being adapted to operate said indicating means through said electric means when said projector 30 means is substantially in a position above said target and said light beam strikes the latter whereby said indicating means may signalize that said target is properly aimed at by said projector means.

Although I have described my improvements with considerable detail and with respect to a certain particular form of my invention, I do not desire to be limited to such details since many changes and modifications in the form, arrangements, proportions and sizes thereof may well be made without departing from the spirit and scope of my invention in its broadest aspect.

Having thus described the invention, what is claimed as new and desired to be secured by 65 Letters Patent is:

1. A game apparatus of the character described comprising a substantially horizontal platform, a plurality of targets successively and spacedly arranged from one another on said platform providing thereon a target course, electrically operable indicating means adjacent each of said targets, light projector means simulating an aircraft for aiming at said targets and having an aperture, said aperture of said projector means being positioned above and facing said target

course and said indicating means, means to move said projector means in a predetermined path above said target course, said projector means being adapted to emit through said aperture a beam of light simulating bomb dropping, said light beam traversing said indicating means when said projector means is moved along said path, and hand-operated switch means simulating bomb releasing mechanism and including an electric circuit, said switch means being adapted to operate said indicating means through said circuit when said light beam is substantially in a position coincident with one of said indicating means to signalize through the latter if its adjacent target is properly aimed at by said projector means.

2. A game apparatus of the character described comprising a housing, a substantially horizontal platform in said housing, a plurality of targets forming a target course disposed at said platform, a group of electric lamp means adjacent each target for illuminating the same, light projector means simulating an aircraft for aiming at said targets and having an aperture, said aperture of said projector means being positioned above and facing said target course and said lamp means, means without said housing to move said projector means in a path substantially coextensive with and above said target course within said housing, said projector means being adapted to emit through said aperture a beam of light simulating bomb dropping, said light beam successively traversing said lamp means when said projector means is moved along said path, and hand-operated switch means simulating bomb releasing mechanism and including an electric circuit, said switch means being adapted to operate through said circuit one lamp of a group of said lamp means when said light beam substantially strikes said group of lamp means to signalize through another lamp of said group if its adjacent target is properly aimed at by said projector means.

3. A game apparatus of the character described comprising a substantially horizontal platform, a plurality of targets forming a target course disposed at said platform, electrically operable indicating means adjacent each of said targets for illuminating the same, light projector means simulating an aircraft for aiming at said targets and having an aperture, said aperture of said projector means being positioned above said target course and said indicating means, means to continuously move said projector means in a predetermined path above and relatively to said target course, said projector means being adapted to emit through said aperture a beam of light simulating bomb dropping, said light beam traversing said target course when said projector means is moved along said path, and hand-operated switch means simulating bomb releasing mechanism and including an electric circuit, said switch means being adapted to operate said indicating means through said circuit when said light beam is substantially in a position coincident with one of said targets to signalize through said indicating means if its adjacent target is properly aimed at by said projector means.

4. A game apparatus of the character described comprising a substantially horizontal platform, at least one target disposed at said platform, electrically operable indicating means positioned below said target for illuminating the same, light projector means simulating an aircraft for aiming at said target and having an aperture, means

- to continuously move said projector means in a predetermined path above and relatively to said target, said projector means being arranged in superposed relation to said target and said indicating means and being adapted to emit through said aperture a beam of light simulating bomb dropping, said light beam being directed toward said platform and traversing said target when said projector means is moved along said path, and hand-operated switch means simulating bomb releasing mechanism and including an electric circuit, said switch means being adapted to operate said indicating means through said circuit when said projector means is substantially in a position above said target and strikes by its light beam the latter whereby to signalize through said indicating means that said target is properly aimed at by said projector means.
5. A game apparatus of the character described comprising a substantially horizontal platform, at least one target disposed at said platform, electrically operable indicating means positioned below said target for illuminating the same, light projector means simulating an aircraft for aiming at said target and having an aperture, means to continuously move said projector means in a predetermined path above and relatively to said target, said projector means being arranged in superposed relation to said target and said indicating means and being adapted to emit through said aperture a beam of light simulating bomb dropping, said light beam being directed toward said platform and traversing said target when said projector means is moved along said path, hand-operated switch means simulating bomb releasing mechanism and including an electric circuit, and electric means coordinated to said target and includ- 5 10 15 20 20
